UNITED STATES PATENT OFFICE.

EUGENE L. GREENEWALD, OF WILKINSBURG, PENNSYLVANIA.

CAN AND THE LIKE.

1,320,466.

Specification of Letters Patent.

Patented Nov. 4, 1919.

Application filed November 7, 1913, Serial No. 799,641. Renewed February 13, 1918. Serial No. 216,976.

To all whom it may concern:

Be it known that I, EUGENE L. GREENEWALD, a citizen of the United States of America, and resident of Wilkinsburg, Pennsylvania, have invented certain new and useful Improvements in Cans and the like, of which the following is a specification.

My invention relates to improvements in cans and the like which may be made of sheet metal or any other suitable material, certain of the improvements being susceptible of use in the construction of cans of paper or other suitable material, and in the construction of closures for containers as will be hereinafter set forth.

Heretofore, in the construction of cans and similar articles comprising a body part and a cover part for the end of the body part, the cover part has generally been so secured to the body part as to form a permanent joint between the body and its head. Such a construction precludes the easy removal of the cover section,—in order to open the can it becomes necessary to cut or otherwise mutilate a part of the can, the cover part or body part or both.

Another objection to joining the cover to the body in the ordinary manner is that the drawing or working of the edge of the cover to form the depending flange which is bent and stretched to form the seal, causes an annular thinner and weakened section a slight distance within the edge of the cover part and at a point where more than elsewhere it is important to have the normal thickness and strength of metal or other material. In other words, the material is stretched, and if the metal of which the device is made is lacquered in the sheet, or before the can is sealed, the coating of lacquer or the like will crack when the cover is applied to the body.

It is the object of this invention to overcome the foregoing and other objectionable features of certain types of cans and similar containers, so as to provide a can or the like to which the cover section is applied in a novel manner and whereby the same may be readily opened by a simple manipulation and without mutilating, tearing, cutting or in any way rupturing the head or body of the same.

A further object is to apply the head or cover to the body and form a seam between

the two by a method in which neither the metal comprising the body nor that comprising the head is strained, stretched or weakened in an appreciable amount.

In general, I carry out the invention in the following manner: A flanged tubular or circular body part of metal or other suitable material is fitted with a disk-like cover part of metal or other suitable material, the peripheral edges of the flange and cover being substantially coincident, the cover resting on the flange and if desired, a suitable gasket or sealing composition may be interposed between the flange and cover part.

The sealing is accomplished by radially corrugating the edges, or by folding or crimping them so as to reduce the outer diameter of the same. The two edges are simultaneously bent to the same extent, to a position alongside the body,—the contiguous body part, the flange and outer edge of the cover part to a width substantially equal to the width of the flange are thus disposed substantially parallel to each other. The 2-wall corrugated seam between the cover and body produces interfitting corrugations in the parts and serves to assist in locking the parts together and against relative rotary movement and has the very important advantage that by suitable means the corrugated edge of the cover may be bent out and when the said corrugations are shallower at several points the cover may be removed without a mutilation of either of the parts.

The cover part may be a flat circular disk of metal or other suitable material and corresponds approximately to the diameter or outside dimensions of the flange on the body part. When the cover part is joined to the grooved or flaring ended body member by a corrugated seam and the flange and edge of the cover part are bent beneath the flare, the plain disk suffices as a cover member and the parts are securely locked together. In the body of uniform section, the cover part is provided with locking extensions or tabs constructed of flexible or other suitable material. The tabs are bent in beneath the flange and when the corrugated seam is formed and the flange and edge of the cover are bent against the side of the body, certain tabs may be of such a length as to project from beneath the parts forming the

seam so that they may be engaged by means of a suitable device to assist in removing the cover. The tabs may be provided on the covers for the bodies having flaring ends, to 5 augment the locking action and to provide means whereby the cover may be more readily loosened and removed. The metal or material of the body part may be non-yielding so that the corrugations will not 10 sink into the material as the parts do not depend on entering or biting into the material for their locking function. The material of the can body and cover are not stretched when the parts are secured 15 together and consequently the body part will be of uniform thickness throughout which is an advantage as it allows the container to be made of thinner material than heretofore. The entire can may therefore be formed and 20 sealed without stretching any of the material thereof.

The objects and novel features of the invention will be apparent from the following detail description, taken in connection with 25 the drawings, in which—

Figure 1 is a perspective view of a can or container embodying my invention, the cover part being shown slightly in raised position to more clearly disclose the manipulation and construction.

Fig. 2 is a sectional view of the can shown in Fig. 1 showing the parts thereof assembled and before they are secured together.

Fig. 3 is a part sectional and part elevational view of the can shown in Fig. 1, the cover being attached to the body by corrugations and the corrugated seamed portion being bent down along the side of the can.

Fig. 3^a is a cross sectional view of Fig. 3 looking in the direction of the arrows at line 3—3 and illustrating the relation of the parts when the detaching tabs are pulled out as the cover is being removed.

Fig. 4 is a sectional view of another can construction embodying my invention.

Fig. 5 is a plan view of a one-piece cover part of metal adapted to be united to a flanged body member by means of corrugations, and releasably locked thereto by integral extensions or tabs.

Fig. 6 is a plan view of a cover part of paper or similar material with attached metal extensions or tabs.

Fig. 7 is a sectional view disclosing a can comprising a body part of paper or similar material with an attached cover embodying my invention.

Fig. 8 is a sectional view disclosing a body part of paper or other suitable material having a metal flange and cover secured thereto.

Fig. 9 is a vertical sectional view showing another can construction embodying my invention.

Fig. 10 is a sectional view of the parts

used in a plain can body made according to this invention, the parts being slightly separated to more clearly disclose the construction.

Fig. 11 is a sectional view of the parts 70 connected together and ready to receive the corrugations or crimps.

Fig. 12 is a view partly in perspective showing the corrugating and bending partly completed.

Fig. 13 is a sectional view of the can body with the cover part removably attached thereto.

Referring to Figs. 1 to 4, of the drawings, 20 designates a metal container or can body 80 which is preferably circular in cross-section although it is to be understood that the body is not necessarily circular in cross section, but may be made rectangular or any other suitable shape, all such suitable shapes being herein broadly included under the designation of "tubular" bodies.

As will appear from Fig. 2, the ends of the can body 20 are provided with the continuous flanges 21 and 22, at the top and 90 bottom respectively, the said flanges being formed on the body 20 in any suitable manner, but preferably so that the flanges and tubular part will be of the same thickness throughout. Circumferential V-shaped 95 grooves or depressions 23 and 24 are formed in the body 20 just within the flanges 21 and 22, respectively, the grooves thus forming the flaring mouths or ends 25 and 26.

The cover part for the bottom of the can 100 body comprises a metal disk 27 of a diameter substantially equal to the diameter of the flange 22 and having its periphery substantially in coincidence with the periphery of the flange.

The bottom 27 is secured to the can by crimping or corrugating and simultaneously bending both the flange 22 and the bottom 27. The corrugations formed are arranged non-concentrically and are deeper at the 110 outer edge of the flange and bottom and as this corrugating operation reduces the actual circumference of both flange and bottom, the edges thereof may readily be bent toward the axis of the can and into the 115 groove 24 as the corrugations gradually increase in depth. When bending the flange and bottom into the groove a resilient bead-like roll may be formed to assist in holding the bottom on. However, the extensive frictional contact between the bottom and the flange, and the fact that both extend inwardly into the groove 24 serves to effect a suitable seal, and a tendency to force the bottom off will simply act to increase the 125 surface frictional contact between the flange and bottom.

The cover part 29 applied to the top of the can body 20 may be in the form of a flat circular disk such as the bottom, but is 130

preferably provided with an approximately V-shaped annular groove 30, the wall 31 of which may be vertical, and the wall 32 of which may be of an inclination to conform 5 to the flare of the portion 25 so that it will seat tightly on the latter and automatically center the cover part on the mouth of the can. The flaring end 25 provides an inner sealing shoulder for supporting the cover 10 part, and an outer shoulder beneath which the edge of the plate-like cover part may be corrugated and bent. It is to be understood that the entire center of the cover part 29 may be depressed, leaving an inclined 15 wall 32, as before, to fit tight against and center the said cover on the mouth of the body. The bead formed by the grooved portion also serves to reinforce the cover and enables the head of the can to resist greater 20 side pressures thereon.

Beyond the groove 30 of the cover and concentric therewith, there is a groove 293 adapted to receive and retain a suitable gasket or sealing composition 292. Preferably 25 an albuminous or similar gasket is inserted in the groove 291 in a liquid state and allowed to solidify. A small soft rubber gasket may also be fitted in the groove. An annular bead 251 is formed at the upper 30 edge of the flaring portion 25 of the body and is of such a size as to fit in the groove 291 and compress the gasket therein as shown in Fig. 3, when the parts are seamed together to assist in forming a hermetic 35 seal. The bead 251 comprises a portion of the resilient bead formed at the end of the can body when the cover is secured to the flange of the body part and bent down.

The edge or periphery of the cover part 40 coincides with the periphery of the flange 21, as in the construction of the bottom. In addition, the cover has a series of spaced integral or attached, yielding extensions or 45 tabs 33, 34 and 35, or 331, 341, and 351, as shown on covers 29 and 291 in Figs. 5 and 6, respectively. It is to be understood that the extensions are preferably spaced apart about 120°, as shown in Figs. 5 and 6, but the number may be increased if desired. It 50 will be seen that the tabs 34, 341, 35, and 351 are longer than the tabs 33, 331, and each long tab is provided at its free end with a hole 36 adapted to receive a part of the can opening implement.

55 The longer tabs may be bent upon themselves intermediate their ends, as indicated in dotted lines in Figs. 2 and 3, and then bent beneath the flange 21, the short tab 33 being also bent beneath the flange. The 60 cover part 20 is thus locked to the body part by the extensions 33, 34, and 35, but as the ends of the extensions 34 and 35 project beyond the edge of the seam formed when the flange 21 and edge of the top 29 are corrugated and bent into the groove 23, they

may be seized with the fingers or a suitable instrument and drawn outwardly. The lock which the extensions effect is thereby released and the corrugations or folds in the cover part 29 may be drawn outwardly, 70 thereby gradually increasing the diameter of the corrugated depending flange formed on the cover until it will finally slip over the beadlike roll 37 formed when the flange 21 is folded or corrugated and bent into the 75 groove 23 with the cover part 29 locked thereto. It is not necessary to force the extension 33 from beneath the inwardly extending seam. The said extension may serve as a hinge about which the cover may 80 be turned when it is raised off the can.

A gasket may be fitted about the inclined wall 32 of the groove 30 in the cover part 29 or it may be arranged in a suitable groove in the flange 21 so as to form a more effective 85 seal. A suitable sealing composition such as albumen, or the like, may also be applied to the abutting faces of the flange and cover section to augment the sealing action. The flange 21 and edge of the cover part 29 may 90 be crimped, folded or corrugated and simultaneously bent into the groove 23 alongside the can body, in the same manner as the bottom part 27 is affixed to the body.

95 It is to be understood that locking extensions may also be provided on the bottom part 27 or they may be entirely omitted from both bottom and top, if desired, the inherent properties of either the bottom or top holding the same in place on the body.

The can body may be equipped with a bottom of the ordinary or any preferred type. The can body may, furthermore, be made up with the bottom attached thereto and the flange 21 thereof corrugated and bent 105 into the groove 23 before the lid 20 is applied thereto. In such a construction locking extensions for the lid may be dispensed with, the lid being set on the mouth of the can so that the groove 30 co-operates to center 110 the cover. To properly place the cover section, it may be provided with several spaced dents and the cover section may be turned so that the dents therein will register with certain corrugations on the inturned body flange. To secure the cover to the can, the cover is corrugated or crimped from its edge 115 onto the bead or roll 37 and simultaneously bent downwardly and into the groove 23, forming in effect a downwardly and inwardly turned corrugated flange on the cover 29, the corrugations thereof finally fitting into the corrugations of the flange 21.

120 The edges of the seams formed by the longitudinal corrugations may be of a slightly smaller diameter than the body portion of the container and will, therefore, not be subject to any knocks which might accidentally loosen the parts or destroy the seal.

125 Referring to Fig. 4, the securing flange at 130

- the mouth of the can body 201 comprises the roll flange or bead 211 formed by rolling the flange so that the edge thereof will not be exposed. Heretofore it has been impossible to apply a seal of the crown type to a wide mouth container because the bead has been faulty in that it lacked resilience. A resilient bead is essential in order to get a hermetic seal with a large diametered cover and such a bead is provided in the roll bead or flange 211. A resilient band may be secured to the can body or the bead may be folded instead of rolled, the essential feature being to provide resiliency. The cover 38 has a depressed portion formed by the groove 301, the depressed portion resting on the inner bead 202 where an additional seal is had. The marginal edge of the cover is rolled so that the raw edge of the cover will be unexposed and so as to form a resilient bead 381 of sufficient resiliency to snap over the bead or flange 211. No locking tongues are required as the bead 381 is sufficiently stiff to hold the cover under the flange 211. The cover 38 may be corrugated as at 382 between the bead 381 and groove 301 to apply the same to the can body or it may be corrugated across the resilient bead as it is applied to the body to confine the edge of the cover beneath the resilient flange 211. The cover may be lifted off by means of a suitable instrument, the corrugations 382 and bead 381 swinging out sufficiently for that purpose. In Fig. 7 I have shown a cylindrical container or can body 40 which may have a suitable bottom and has the flaring portion 41 at its mouth. A continuous flange 42 extends around the upper edge of the flaring portion 41, as is shown in dotted lines. The flange 42 may be corrugated and bent in beneath the flaring portion 41 which forms a shoulder or bead at the end of the can beneath which the edge of the cover part 43 may be corrugated and bent. The cover part may be a flat blank, with or without extensions or a grooved blank with or without extensions, such as shown in Fig. 5. In the arrangement indicated in dotted lines in Fig. 7, the edges of the flange 42 and cover 43 coincide and any suitable sealing means or composition, as heretofore described, may be disposed between the two. A plurality of cover locking and detaching extensions or tabs 44 are arranged about the edge of the cover and when the cover and flange are corrugated and bent down, the tabs extend a short distance inside the edge of flange 42 and are disposed between the downturned flange 42 and the body of the can. The tabs may be provided with suitable apertured extensions corresponding to those disclosed in Figs. 5 and 6 so that

they may be readily engaged with a suitable instrument and removed from their locking relation with the flange 42. The tabs may be entirely dispensed with if desired, as the inwardly extending corrugated flange formed on the cover part will engage beneath the shoulder formed by the flaring portion 41 of the container and lock the cover onto the can sufficiently tight for certain purposes.

In Fig. 8 I have shown one end of a cylindrical can body 45 made of paper or other suitable material. At each end of the body 45 I have secured a right angular sheet metal member 46, one part 47 of which encircles the end of the can body and has the sharp projections 48 which may be forced through the body to the opposite side and clenched to secure the member 46 to the body 45. A suitable sealing or cementing composition may be introduced between the part 47 and the can body so that there will be no possibility of leakage through the holes made by the points 48. The member 46 has an outwardly projecting portion 50, which is disposed at right angles to the can body at its upper edge. The portion 50 constitutes an attached metal flange for the paper can, receptacle, or tube and is provided so that a metal cover may be detachably connected thereto by corrugations. It is to be understood that the cover 51 may be metal or non-metal and the body part may likewise be of a metallic or non-metallic material. The lid 51 may have a groove 52 to center the same in the mouth of the can and to also provide a wall 53 of a surface comprising a centering and sealing means co-operating with the inner wall of the container 45. The center of the cover may be depressed and a suitable gasket or sealing composition or both may be located between the adjacent faces of the flange 50 and cover 51.

For the purpose of detachably uniting the cover to the body, corrugating or crimping means may be applied to form a seam between the two parts comprising longitudinal corrugations, the edges of the flange and cover being simultaneously bent down to a position alongside the body of the can. As before indicated, suitable locking and detaching tongues may be provided at the edge of the cover part for engaging beneath the edge of the flange to detachably lock the parts together.

In Fig. 9 I have shown a completed tubular metal can, the body 55 of which is formed at its ends with inwardly extending depressions 56 and 57, and outstanding continuous flanges 58 and 59 located at the ends of the depressions. The bottom 60, provided with a centering depression or groove 61 may be detachably applied to one end of

the body 55 by longitudinal corrugations, a gasket and sealing composition being located between the bottom and flange, if desired. Locking tabs formed integral with the edges of the bottom will serve to lock the parts together when the flange and edge of the bottom have been bent into the depression and alongside of the body, the depressions being provided so as to fit the seam within the borders of the body in order that the can will be substantially the same diameter throughout its length. In attaching the bottom, the locking tabs or extensions need not be bent on themselves to form detaching tabs, as it is not customary to remove the bottom; however, the locking tabs are short enough so that they may readily be bent down by a suitable instrument to unlock the parts and permit the removal of the bottom by bending out the corrugations thereof.

The cover 62 has a centrally depressed portion or a groove to center the same in the mouth of the can and to form a wall 63 extending into the mouth of the can against which a suitable plunger may rest while the flange 59 and overlapping edge of the cover are being corrugated and bent alongside the can into the depression 57. A suitable gasket, a coating of sealing substance or both may be applied between the flange and cover. The cover may be provided with integral locking, or locking and detaching tabs or extensions 64 which extend beneath the edge of the flange to detachably lock the parts together. The detaching tabs being doubled under the edge of the flange assist in locking the parts together. The ends of the apertured tabs project a short distance from beneath the edge of the seam, and being flexible they may be engaged by a suitable instrument and drawn out. This unlocks the parts and a continued pulling on the tab increases the diameter of the cover flange due to the tendency to straighten out the corrugations therein at several points, as indicated in Figs. 1 and 3^a, so that the cover may be raised off the body. A bead 65 extending around the body of the can serves to reinforce the body and may provide a fulcrum for an instrument used in prying out the corrugated seam.

In Fig. 10 I have illustrated a common form of sheet metal can body 66 which has the integral outstanding continuous flanges 67 and 68 at its opposite ends forming a can body having the material therein of uniform thickness throughout.

The bottom part 69 has a plurality of integral locking projections at its edges which are bent beneath the flange 67 before the two parts are seamed together by means of longitudinal corrugations. The can body

is uniform in diameter and the seam is bent alongside the body simultaneously with the corrugating, folding or crimping operation. As in other forms described, a suitable sealing composition or a gasket 671 or both may be inserted between the flange and bottom part. A plunger may be inserted into the interior of the body when the parts are corrugated together to prevent the collapse of the body.

The cover part 70 may be similar in construction to the bottom part except that instead of three locking tabs I preferably provide one locking projection 701 and two apertured flexible locking and detaching tabs 702 all integral with the cover at its edge. In Fig. 10 an edge view of the cover blank is shown which is in most respects similar to the blank shown in Fig. 5. In Fig. 11 one of the locking and detaching tabs 702 is shown in section, a part 71 being bent to lie directly beneath the flange 68 and extending inwardly to the can body, the part 72 of the tab being bent at right angles to the part 71 and lying along the can body.

In Fig. 12 an elevation of a portion of a partly finished corrugated seam is shown and also a sectional view of the same, while Fig. 13 shows a view in section of the completed seam which detachably secures the head or cover to the body.

It will appear from the foregoing description that I have shown a construction in which a metallic or non-metallic cover part is secured to a metallic or non-metallic tubular part by means of corrugations and suitable locking devices, thereby providing a can with a hermetic closure which may readily be removed from the body without cutting or otherwise mutilating the parts.

The edge of the cover and a flange on the tubular part are turned over by a concurrent corrugating and bending operation, and there is, consequently, no drawing or stretching of the metal in either part. The locking tabs or tongues may be comparatively short, approximately five times as long as the thickness of the metal of the can body. The corrugated down-turned edges may be pulled out to release the locking tongues or the latter may be of sufficient length to be accessible to a suitable instrument from the exterior.

In all of the devices shown the corrugations are radial or disposed in planes radial to the axis of the top and body, and form a solderless seam, *i. e.*, a two-wall seam free from solder.

The invention may be applied to sheet metal cans, containers of paper and the like, to vitreous containers or non-vitreous containers of flexible material.

As fully set forth, a satisfactory joint or

seam may be formed by the coöperating beveled surfaces of the corrugated flange, cover and body, the latter being slightly indented when the corrugation is done on the exterior. The corrugations reduce the outer diameter of the cover part and flange part so that bending the same alongside the body will not require any change in the metal as bulging or stretching.

10 In case the joint formed is not sufficiently tight, suitable sealing means may be inserted between the cover and the flange or body of the can.

The cover parts having grooves or depressions therein automatically center themselves in the mouth of the can body and seat on the edge rim or on the ledge formed by the flaring part of the body. Locking tabs or tongues may be provided for the cover parts or the tongue may be dispensed with. Each of the tabs is flexible so that it may readily be bent without breaking. Certain of the tabs may be bent on themselves intermediate their ends so that the free ends thereof may interlock with the corrugated seam and project from beneath the seam so as to be accessible for the purpose of pulling out the corrugations of the cover part. The corrugations take up the excess peripheral length of the edges of the flange and cover, decreasing in depth from the edge inwardly. The longitudinal corrugations, folds or creases form interlocking means between said flange and cover to prevent the movement of the latter around the flange. The corrugation of the tab and tubular part together keeps the tab tight. According to the foregoing description, it will be apparent that numerous modifications are possible without departing from the spirit of the invention, and, therefore, I do not wish to be limited to the exact details as shown and described.

Having thus fully described my invention, what I claim is:—

1. In combination, a sheet metal body part formed with a flange, and a cover part detachably secured to said body part by edge corrugations in the cover part, said edge corrugations forming a substantially continuous corrugated edge which extends under said flange.

2. In combination, a container having a cover engaging shoulder, a metal cover for closing said container, said cover being formed from a blank having a substantially flat peripheral edge portion, said flat peripheral edge portion being bent down and secured under said shoulder by corrugating and reducing the outer diameter of said flat peripheral edge portion, said cover being held in place on said container by the inherent resiliency of the corrugated portion thereof.

3. In combination, a tubular body part having a flange, and a cover part, said flange and a portion of said cover part being corrugated and bent down together, said bent down portion and flange being arranged outside the tubular part, the corrugations formed extending longitudinally of the body part.

4. In combination, a container or the like having a cover engaging shoulder, a cover for closing said container, said cover being formed from a blank having a gasket attached thereto, said blank having a substantially flat peripheral rim portion, said rim portion being bent down and secured under said shoulder by corrugating and reducing the outer diameter of said flat peripheral rim portion whereby a corrugated resilient part is provided to hold said cover in place and to hold said gasket in sealing position.

5. In a container or the like, the combination of a tubular body part provided with an outer flange, said flange having the surface thereof disposed substantially parallel to the adjacent surface of the body part, and a cover part secured to said body part and having a flange disposed alongside the flange on the body part, said flanges having interfitting corrugations.

6. In a container or the like, the combination of a tubular body part provided with an outer flange, said flange extending longitudinally of the body part, a cover part having a flange disposed alongside the flange on the body part, said flanges having interfitting corrugations, and means detachably securing said cover part to said body part so that the entire cover part may be readily detached from the body part.

7. A container comprising a tubular body part and a cover part detachably secured thereto by corrugations near the edge of one of said parts and also by projections on one of said parts, said projections engaging the other of said parts.

8. A container or the like comprising a tubular body having a resilient cover-engaging shoulder, and a removable cover formed from a blank having a substantially flat rim portion, said rim portion being provided with transverse corrugations throughout its length and being bent down and having its edge extending under said resilient shoulder, said transverse corrugations extending to the edge of the bent-down portion and uniformly decreasing in depth from said edge to the bend in the rim and providing a resilient expandible edge for said rim whereby said cover is detachably secured to the resilient shoulder on said body by the corrugated portion thereof.

9. In combination, a tubular body part

- formed with a flange and a cover part secured to said flange by a two-wall corrugated seam between said flange and cover part, said seam being free from solder. 65
5. 10. In combination, a body part having an outer flange, a cover part having an extension, said parts being attached together by corrugations in the edge of the cover part, said extension projecting under the flange of the body part and locking the parts together and also projecting from beneath the corrugated edge of the cover part so as to be accessible for the purpose of detaching the cover. 70
10. 11. In combination, a tubular body part, a cover part therefor, means attached to one of said parts detachably locking it to the other part, and a corrugated seam between said parts. 75
15. 12. In a container, the combination of a tubular body part having a flange, a cover part having a flange at its edge, a projection on one of the parts adapted to engage the other part, and a corrugated seam between said flanges, said seam and projection detachably uniting said parts. 80
20. 13. In a device of the class described, the combination of, a tubular metal body part having a circumferential depression near one end, and a cover part formed from a blank having a substantially flat peripheral flange, said flange being provided with corrugations and united to said body by said corrugations, a part of said flange being disposed in said depression, said cover part being held in place by the inherent resiliency of the material comprising the flange portion thereof. 85
25. 14. The combination of a tubular body part having a down-turned flange, and a cover part having a flange seamed to the first-mentioned flange and detachable therefrom without rupture of either of said parts, said cover part having an extension underlapping the body flange and disposed between the latter and the body, a portion of the extension depending beneath the flanges. 90
30. 15. In combination, a tubular body part having a depression of less diameter than the diameter of the body part, a cover part seamed to said body part and having a portion thereof extending into said depression, and an extension on one of said parts engaging the other part to lock said parts together. 95
35. 16. The combination with a sheet metal body part having a flange at one end and a depression beneath said flange, of a sheet metal cover part seamed to the flange of the body part, the edges of the seamed-together parts extending into said depression and disposed outside said body. 100
40. 17. In combination, a tubular body part having a flange, and a groove adjacent said flange, and a cover part detachably secured to said flange by corrugations in the edge of one of said parts, the edges of the flange and cover part being disposed in said groove. 105
45. 18. The combination of, a tubular body part and a cover part secured to said body part by interfitting corrugations, extending throughout the peripheries of said parts, said corrugations being disposed in substantially radial planes and uniformly decreasing in depth from the edges of said parts, and a releasable locking device on one of said parts adapted to engage the other part and releasably lock said parts together. 110
50. 19. The combination of a tubular body part flaring at one end, and a cover part having an inclined wall fitting the flaring end of the body part and secured to the body part by corrugations in the edge of said cover part, one of said parts having a projection locking the same to the other part. 115
55. 20. The combination of a tubular part having a flange, and a cover part removably secured thereto by a corrugated seam, said seam being free from solder. 120
60. 21. In a can, the combination of a tubular body part having a flaring portion and an outer flange adjacent the flaring portion, a cover part provided with a depressed portion having an inclined wall fitting said flaring portion, said parts being joined together by a two-wall corrugated seam. 125
65. 22. In a container, the combination of a body part and a cover part, said cover part being secured to said body part by corrugations in the edge of said cover part and being locked to the body part by extensions on said cover part. 130
70. 23. In a can, the combination of a body part having an interior shoulder, and a cover part having a flange and a depressed portion co-operating with said shoulder, said parts being secured together by interfitting corrugations. 135
75. 24. In a container, the combination of a body part having an interior shoulder, and a cover part formed from a blank having a substantially flat peripheral flange and a depressed portion within said flange, said depressed portion fitting said shoulder to provide a seal thereat, said flat peripheral flange of the blank being corrugated and bent down into engagement with a portion on said body part to secure the cover in place thereon. 140
80. 25. The combination of a tubular body part having a bead adjacent one end, a cover part seamed to said body part by interfitting corrugations and having a groove adapted to contain a sealing material, said bead being adapted to fit said groove and extend into the sealing material to form a seal between the parts. 145

26. The combination of a tubular body part having a resilient bead adjacent one end and a flaring mouth, a cover part formed with a flange, said cover part having a depressed portion fitting the interior of the body and resting on said flaring mouth, said cover being secured in place by corrugating and bending down the flange of the cover part. 50
- 10 27. In a can or the like, the combination of a tubular body portion, and a member having a part extending over the end edge of said body, said body and member having an endless series of interfitting radial corrugations securing them together. 55
- 15 28. The combination of a flanged cylindrical part, a plate-like part, and a seam for securing said parts together without solder comprising interfitting radial corrugations in said flanged cylindrical part and said plate-like part. 60
- 20 29. In a can or the like, the combination of a tubular body part having a resilient exterior shoulder at one end, and a cover comprising a member having a corrugated flange extending under said shoulder, said flange being bent upon itself at its lower edge. 65
- 25 30. In a device of the class described, the combination of a tubular metal body part having an exterior shoulder at one end thereof, and a cover therefor comprising a metal member having a corrugated flange extending beneath said shoulder, said corrugated flange consisting of the radially corrugated and downwardly bent peripheral edge portion of said metal member. 70
- 30 31. The combination of a circular member, and a disk-like member, portions of said members being united by interfitting corrugations and each of said corrugated portions being bent at an angle to the position occupied by said portions at the beginning of the uniting operation, said corrugations being disposed in radial planes. 75
- 35 40 45 32. In a container, the combination of a body part having a resilient bead adjacent one end, and a cover part removably attached to said body part, said cover part having radial corrugations in the edge thereof disposed adjacent said bead. 80
33. The combination with a tubular body part having an exterior resilient bead at one end, of a cover part therefor having a depending corrugated flange extending inwardly beneath said bead, the corrugations in said flange being parallel to one another throughout the extent of the flange and disposed longitudinally to said body part. 85
34. The combination with a tubular body having an exterior resilient bead at one end and an exterior circumferential groove below said bead forming an interior annular part within said body of smaller internal diameter than the mouth of said body, of a cover for said body having a resilient expansible flange extending around and below said resilient bead and terminating adjacent said exterior groove. 90
35. In a container, the combination of a body having an exterior resilient bead at its upper edge and a groove in the exterior wall of the body below said upper edge, and a cover removably secured to said body and comprising a flange having corrugations therein to provide a resilient expansible edge therefor, said corrugated edge extending beneath said exterior bead and opposite said exterior groove. 95
36. The combination with a container having an exterior resilient shoulder adjacent the mouth thereof, of a removable closure for said container comprising a cover part adapted to close said mouth and a rim flange depending below said cover part and having transverse corrugations therein providing a resilient expansible edge on said closure extending beneath said resilient shoulder to removably secure said closure to said container. 100
- In testimony whereof I affix my signature in presence of two witnesses.
- EUGENE L. GREENEWALD.
- Witnesses:
- ARTHUR L. BRYANT,
B. M. OFFUTT.
